[57] CLAIM

The ornamental design for a housing for photoelectric control, as shown and described.

DESCRIPTION

FIG. 1 is a front and top-right perspective view of a housing for a photoelectric control showing the new design;

FIG. 2 is a front elevational view thereof;

FIG. 3 is a rear elevational view thereof;

FIG. 4 is a right-side elevational view thereof, the side opposite that shown being a mirror image;

FIG. 5 is a top plan view thereof; and,

FIG. 6 is a bottom plan view thereof.

The broken lines in FIGS. 1, 2, 3 and 4 are included for the purpose of illustrating environmental structure only and form no part of the claimed design.
